UNITED STATES PATENT OFFICE.

MATTHEW J. WELLING, OF CHICAGO, ILLINOIS, ASSIGNOR OF ONE-HALF TO JOHN HOWARD McELROY, OF CHICAGO, ILLINOIS.

FEEDING MECHANISM.

1,075,276.

Specification of Letters Patent.

Patented Oct. 7, 1913.

Application filed March 5, 1913. Serial No. 752,039.

To all whom it may concern:

Be it known that I, MATTHEW J. WELLING, a citizen of the United States, and a resident of Chicago, in the county of Cook and State of Illinois, have invented certain new and useful Improvements in Feeding Mechanism, of which the following is a full, clear, and exact specification.

My invention is concerned with feeding mechanism intended primarily to feed strips of tin or sheet-metal to a punch press or other automatic machine by a step-by-step movement, and is designed to produce a device of the class described in which the step-by-step feed shall be accomplished by a continuous rotary movement, instead of the reciprocating movement heretofore employed.

My invention is further concerned with certain novel combinations of elements, as hereinafter more particularly specified.

To illustrate my invention, I annex hereto four sheets of drawings, in which the same reference characters are used to designate identical parts in all the figures, of which,—

Figure 1 is a side elevation of a punch press having my invention applied thereto; Fig. 2 is a front elevation of the same as it would appear looking at it at right angles to the line of movement of the punch; Fig. 3 is a plan view in section on the line A—A of Fig. 1; Fig. 4 is a similar view in section on the line B—B of Fig. 1, with a portion of the casing broken away; Fig. 5 is an enlarged detail in section on the line C—C of Fig. 3; Fig. 6 is a view in section on the line D—D of Fig. 5; Fig. 7 is an enlarged section in detail on the line E—E of Fig. 6; Fig. 8 (Sheet 2) is a perspective view showing the under side of a plate; Fig. 9 is an enlarged view through one of the cups, showing the valve mechanism therein; and Fig. 10 is a detail in section, on a large scale, on the line F—F of Fig. 3.

I have shown my invention as applied to a punch press having the base 10 supported on the legs 11 in the customary manner. It may be applied to any sort of an automatic machine where a similar step-by-step feed is necessary, but I have shown it as attached to the aforesaid punch press as being the machine with which it was primarily designed to coöperate. The punch press is of the ordinary construction, and I have shown the automatic feeding mechanism as

actuated from the main shaft 12 of said press.

As seen in Figs. 1 and 2, a bracket casting 13 is bolted to the base of the press, and the inclined front side 14 thereof has projecting therefrom a shelf 15 which serves as a support for the blank strips 16 piled thereon. The strips 16 must be raised one by one from the pile at the proper time, and for this purpose I employ the following mechanism: The shaft 12 has secured on one end thereof a miter gear 17 which meshes with a similar gear 18 secured on the upper end of the shaft 19, which is journaled at its upper end in a suitable bearing bracket 20 extending out to one side from the main frame of the punch press, and at its bottom in a bearing recess 21 formed in the plate 38, to be hereinafter described. The shaft 19 has secured on the lower end thereof a spur-gear-wheel 22, which, if the feeding mechanism is designed to feed each strip in four steps, will have one-fourth the diameter of the spur-gear 23, which is rigidly secured on the short shaft 24 journaled in the bearing bracket 25, whose axis is parallel to the axis of the bracket 20. The upper face of the spur-gear-wheel 23 has secured thereon the face cam 26, and the cam groove 27 thereof is occupied by the anti-friction roller 28 secured on the lower end of the vertical arm of the bell-crank-lever 29, which is fulcrumed on the bearing bracket 30, also secured to the adjacent side of the frame of the punch press. The outer end of the horizontal arm of the bell-crank 29 is pivotally connected by a pin passing through a slightly elongated slot to the ears 31 of the bar 32, which has at its ends bearings 33 through which pass the tubes 34 of the vacuum cups 35 secured on the lower ends thereof. These tubes 34 are adapted to slide through stationary bearing sleeves 36 which are supported by brackets 37 from the cover plate 38, which is suitably supported, as will be hereinafter described, from the bracket 13. The sockets 33 of the bar 32 are provided, as indicated in dotted lines in Fig. 3, with spring-pressed plungers 39, which coöperate with the tubes 34 to hold them in frictional engagement with the sockets 33. The upper ends of the tubes 34 are suitably connected, as seen in Fig. 5, with a transverse tube 40 from which the air is constantly being pumped. As seen

in Fig. 9, the tubes 34 have their lower ends closed and an aperture 41 is made in one side, with which coöperates the ground end of a lever 42 pivoted at 43 in ears supported on the interior of the cup and tending to hang by gravity so that the aperture 41 will be closed. With this arrangement, the vacuum cup is not operative until it is lowered upon the sheet of tin, when the contact of the tin with the lower end of the lever 42 will rock the latter so as to open the aperture 41, when the vacuum will be formed in the cup.

The operation of this lifting or separating mechanism for the tin blanks will be apparent. At each four operations of the press, the cam 26 will be given one complete rotation, and this, acting through the bell-crank, will raise and lower the cups. As the cups are lowered, the tubes 34 move with the sockets 33 until the cups 35 strike the uppermost plate of tin, when the downward movement of the tubes must cease, and thereafter the sockets 33 slide down against the spring pressure of the plungers 39 until the end of the stroke is reached. During the return stroke, the cups rise with the tubes 34 until the collars 44 contact with the lower ends of the sleeves 36, after which the sockets 33 must slide on the tubes 34. The tubes 34 stop always in the same position, with the inner edge of the blank 16 on the under side of the cup 35 just engaging the under side of the forward edge of the intermediate plate 45, which is shown in perspective in Fig. 8. To feed the blanks 16 thus raised quickly into the slot formed between the surface 46 of the intermediate plate 45 and the upper surface of the horizontal portion 47 of the bracket 13, and against the stop 48 formed on the intermediate plate 45, I employ a sliding plate 49, which is mounted to slide in suitable ways formed in the cover plate 38, and which is provided at its forward end with two hooks 50, the lower ends of which extend just below the level of the sheets of tin 16 held up by the cups 35. A helically-coiled contractile spring 51 secured at one end to a bracket 52 and at the other end to the center of the rear of the plate 49, tends to pull said plate 49 to the rear, and its movement is controlled by the anti-friction roller 53 journaled on the upper side of said plate and co-operating with a cam 54 secured on the under side of the gear-wheel 23. The design of this cam is shown in Fig. 4, where it will be seen that there is a surface 55 extending to the center of the cam, so that when the cam rotates far enough for the anti-friction roller 53 to reach this surface, the spring 51 will then be free to draw the plate rapidly to the rear, and thus carry the sheet of tin into the guide slot and against the shoulder 48. This inward feed of the sheet, of course,

must be rapid, as it must occur between one of the four step-by-step feed movements given to each complete rotation of the spur-gear-wheel 23.

The step-by-step feeding mechanism to be now described comprises the main feature of novelty of my invention, although the combinations heretofore described are specifically new.

The shaft 19 has secured thereon, above the spur-gear-wheel 22, a small sprocket wheel 56 which is connected by a sprocket chain 57 with a similar sprocket wheel 58 secured upon the upper end of a short shaft 59 journaled in stationary bearings 80 and 45. This shaft has secured thereon a spur-gear-pinion 60, and there are three other similar spur-gear-pinnions 60 loosely mounted on three stub shafts 61, one of which is shown in Fig. 7. There are three idle spur-gear-wheels 62 which are journaled on headed pins secured in the outer ends of the arms 63, which are mounted on the stub shafts 61. The shafts 61 have collars 64 thereon, and their lower ends are threaded and pass through elongated slots 65 formed in the horizontal portion 47 of the bracket casting 13. These collars 64 rest in correspondingly large recesses in the ends of the arms 63, and by the connections thus shown, it is possible to space the four spur-gear-wheels 60 apart any desired distance within the intended range of adjustment so as to secure different lengths of the step-by-step feed. It will be apparent that the shafts 61 can be shifted in their slots 65, and when they are spaced apart the desired distance, the arms 63 are swung to the proper angle to bring the spur-gear-wheels 62 in proper mesh with the spur-gear-wheels 60, after which the nuts 66 on the threaded ends of the shaft 61 are tightened up and the parts are held in their desired position of adjustment.

The actual step-by-step feeding of the sheets of tin is accomplished by anti-friction rollers 67, which are preferably of very hard metal, which are suitably journaled on the outer ends of the feed arms 68, which are pivoted at their other ends on ears 69 extending upward from the spur-gear-wheels 60. A helically-coiled expanding spring 70, interposed between the under side of the slotted portion of the arm 68 and the spur-gear-wheel 60, serves to press the anti-friction rollers 67 up against the under surface of the intermediate plate 45. The action of this step-by-step feeding mechanism will now be apparent. Supposing that a sheet 125 of tin 16 has been fed by the other mechanism into the position shown in Fig. 6. The shaft 19, through the connections described, rotates all the spur-gear-wheels 60, and the three inner anti-friction rollers 67 will pass 130

through notches 71 in passing from the surface 72 of the intermediate plate 45 to the surface 46 of said plate. The notches 71 are not deep enough to permit the anti-friction rollers 67 to engage the edge of the plate 16 which is now resting against the offset 48, but said anti-friction rollers 67 engage the under side of the body of the plate, and do not serve to materially displace the same. The outermost anti-friction roller 67, however, is free to engage the rear end of the sheet 16, and as it moves forward from the position shown in Fig. 6, it will feed the sheet far enough so that as the second anti-friction roller 67 comes around on the succeeding movement, the end of said sheet will be in position to be engaged by the end of said second roller, and so on until the sheet is fed entirely through, and at the end of the last feed of the sheet, the spring 51 will act to bring a fresh sheet into place.

I have also shown, in connection with my feed mechanism, a "kick-off," which consists of an arm 73 having a pawl 74 pivoted on its lower end so that said pawl can swing to the right of the position shown, but not to the left, and said pawl will be spring-pressed in the customary manner of these devices. The arm 73 is rigidly secured on a rock shaft 74a suitably journaled in bearings formed in the frame of the press, and a short arm 75 is secured on the other end of said rock shaft. This arm 75 is engaged by a pin 76 carried by the spring-pressed rod 77, mounted to slide in suitable bearings in the framework of the press and having an anti-friction roller 78 at the outer end thereof coöperating with a cam 79 secured on the upper end of the shaft 24. A helically-coiled expanding spring 80 interposed between the end of the rod 77 and a bearing 81 serves to hold the rod 77 in its retracted position, in which the arm 73 hangs vertically. When the cam 79 comes into action, it thrusts the rod 77 rapidly to the right, and this swings the arm 73 to the right very quickly, and the dog 74, which has engaged an aperture in the sheet of tin which is ready to be discharged, by this rapid movement throws the sheet clear of the machine so as to be out of the way of the next sheet that is fed thereto.

I preferably provide suitable spring mechanism for holding the plates 16 of tin in the guideway or slot, and for this purpose I may employ the construction best shown in Figs. 3, 4 and 10, where it will be seen that I provide three tubes 82 associated with the cover plate 38 and extending down through apertures in the intermediate plate 45. The middle one of these three tubes will extend through an elongated slot 83 formed in the reciprocating plate 49. Mounted in these tubes are spring-pressed plunger-rods

84 having heads 85 on the lower ends thereof with the edges beveled off so that a sheet tin thrust into the guideway will raise the plunger against the resistance of the helically-coiled expanding spring placed in the tube between the head 85 and the adjusting nut 87 threaded in the top of the tube 82, by which the tension of the spring is regulated to secure the desired pressure. These plungers 84 are opposed to the angles 88 which are formed in the casting 47, and furnish as much support for the blank 16 as is convenient and still leave clearance for the anti-friction rollers 67.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

That which I claim as new, and desire to secure by Letters Patent of the United States, is:

1. In a feeding device, the combination with a rotating shaft parallel to the axis of the press, a cam carried by the shaft, and means for rotating the same; of a bell-crank lever having a vertical arm coöperating with the cam, and a horizontal arm; a tube supported from the horizontal arm, and means for guiding the tube.

2. In a feeding device, the combination with a rotating shaft parallel to the axis of the press, a cam carried by the shaft, and means for rotating the same; of a bell-crank lever having a vertical arm coöperating with the cam, and a horizontal arm carrying a cross-head; tubes sliding in said cross head, means for guiding the tubes; and friction devices interposed between the cross-head and the tubes, for the purpose described.

3. In a feeding device, the combination with a rotating shaft parallel to the axis of the press; a cam carried by the shaft, and means for rotating the same; of a horizontally sliding hook-member coöperating with the cam, and a spring to return the hook member.

4. In a feeding device, the combination with a rotating shaft parallel to the axis of the press, two cams carried by the shaft, and means for rotating the same; of a bell-crank lever having a vertical arm coöperating with one of the cams, and a horizontal arm; a tube supported from the horizontal arm, means for guiding the tube; a horizontally sliding hook-member coöperating with the other cam, and a spring to return the hook member.

5. In a feeding device for punch-presses, the combination with a rotating shaft parallel to the axis of the press, a cam carried by

the shaft, and means for rotating the cam; of a horizontal spring-pressed plunger extending through the frame of the press, a rock shaft at right angles thereto extending 5 through the frame of the press, an arm on said rock-shaft engaged by the rod near the axis of the rock-shaft, and a kick-off arm depending from said rock-shaft.

6. In a feeding device for punch-presses, 10 the combination with a rotating shaft parallel to the axis of the press, three cams carried by said shaft, and means for rotating the same; of a bell-crank lever having a vertical arm coöperating with one of the 15 cams, and a horizontal arm; a tube supported from the horizontal arm, and means for guiding the tube; a horizontally sliding hook-member coöperating with another of said cams, and a spring to return the hook-member; a horizontal spring-pressed plunger extending through the frame of the press and reciprocated by the third cam; a rock shaft at right angles to the plunger also extending through the frame of the 25 press, an arm on the rock-shaft engaged by the plunger near the axis of the rock-shaft, and a kick-off arm depending from said rock-shaft.

7. In a device of the class described, the 30 combination with a guideway, of a series of rotating, step -by -step feeding members swinging through said way during a portion of their rotation and acting to feed only during said portion, and means for rotating 35 said members.

8. In a device of the class described, the combination with a guideway, of a series of rotating, step -by -step feeding members swinging through said way during a portion 40 of their rotation and acting to feed only during said portion, means for rotating said members, and means for adjusting the distance between said members without disengaging the rotating means.

45 9. In a device of the class described, the combination with a guideway, of a series of rotating step -by -step feeding members swinging through said way during a portion of their rotation and acting to feed only 50 during said portion, eccentrically mounted anti-friction rollers on said members, and means for rotating said members.

55 10. In a device of the class described, the combination with a guideway, of a series of bearing shafts mounted therein, rotating wheels journaled on said shafts, spring arms

extending transversely of the shafts, contact members carried by the outer ends of said arms and swinging through said way during a portion of their rotation and acting to feed only during said portion, and means for rotating said wheels.

11. In a device of the class described, the combination with a guideway having a shoulder at its rear edge against which the 60 sheet to be fed rests, of a series of rotating members swinging through said way on one side of the sheet therein, said way being partially cut away on one side to permit said swinging of the rotating members, contacts carried by said members, and openings in said shoulder to permit the passage of the contacts.

12. In a device of the class described, the combination with a supporting member having a recess in its upper surface, of a plurality of rotating members journaled in said recess, arms pivoted on said members, contacts carried by the free ends of the arms, springs tending to throw the arms upward, 80 means for rotating said members, a plate above said supporting member having a shoulder thereon coöperating with the upper surface of the supporting member to form a way, and recesses in the shoulder to 85 permit the passage of the contact members.

13. In a device of the class described, the combination with a supporting member having a plurality of slotted apertures therein, of a corresponding plurality of bearing 90 studs mounted therein, means for securing said bearing studs in any desired position in the slots, shoulders on said studs, gear wheels journaled thereon above the shoulders, arms interposed between the 95 shoulders and the supporting members, bearing pins carried at the outer ends of the arms, idle gear-wheels on said pins meshing with the first mentioned gear-wheels, contacts carried by the first mentioned gear-wheels, a plate over the supporting member forming a guideway and having a shoulder, recesses in said shoulder to permit the passage of the contacts, and means for rotating said gear-wheels.

105 In witness whereof, I have hereunto set my hand and affixed my seal, this 28th day of February, A. D. 1913.

MATTHEW J. WELLING. [L. S.]
